Primary Examiner — Jonathan J Han(74) Attorney, Agent, or Firm — Banner & Witcoff, Ltd.(57) CLAIM

The ornamental design for a shoe as shown and described.

DESCRIPTION

FIG. 1 is a front perspective view of a shoe showing my new design; and

FIG. 2 is a side view thereof; and,

FIG. 3 is a rear perspective view thereof.

The broken lines immediately adjacent to the shaded area define the bounds of the claimed design and form no part thereof. The four racetrack shaped elements shown in broken lines within the shaded area represent eyelets that form no part of the claimed design. The broken lines and unshaded regions in the two lower panels represent the internal regions of the panels that form no part of the claimed design. The broken lines depicting the remainder of the shoe form no part of the claimed design.
